UNITED STATES PATENT OFFICE.

JOSEPH A. F. NEVINS AND FORREST A. SUTHERLAND, OF MILLINOCKET, MAINE.

MACHINE FOR HANDLING ROLLS OF PAPER.

1,354,993.

Specification of Letters Patent.

Patented Oct. 5, 1920.

Application filed July 12, 1917. Serial No. 180,084.

To all whom it may concern:

Be it known that we, JOSEPH A. F. NEVINS and FORREST A. SUTHERLAND, citizens of the United States, residing at Millinocket, in 5 the county of Penobscot and State of Maine, have invented certain Improvements in Machines for Handling Rolls of Paper, of which the following description, in connection with the accompanying drawings is a 10 specification, like reference characters on the drawings indicating like parts in the several figures.

This invention is concerned primarily with the handling and transportation of 15 large rolls of paper although the apparatus provided by the invention may also be used in the handling of other articles. These rolls of paper come from a paper making machine in a horizontal position and in the 20 course of shipping or storing them it is necessary to "upend" them; that is, to set them up in an upright position. Inasmuch as these rolls are extremely heavy it is difficult to perform this operation with any of 25 the machines or apparatus ordinarily available, and it is the chief object of this invention to devise a machine with which this handling of these rolls of paper can be readily accomplished.

30 The various features of the invention will be readily understood from the following description when read in connection with the accompanying drawings, in which:

Figure 1 is an angular view showing a 35 machine embodying the invention in its preferred form;

Fig. 2 is an angular view showing the machine in its load receiving position;

Figs. 3 and 4 are diagrammatical views 40 showing different positions of the mechanism that up-ends the roll of paper;

Figs. 5 and 6 are diagrammatical views showing, in different positions, the mechanism that delivers the load to the up-ending 45 mechanism; and

Fig. 7 is an angular view showing the mechanism by which the angular adjustment of the trucks that support the machine is effected.

50 The machine shown comprises a portable frame in which the operating parts are mounted, an upending cradle designed to receive a roll of paper in a horizontal position and arranged to be swung into substantially an upright position, and a transferring cradle which is arranged to receive

the roll and deliver it to the upending cradle.

Referring now to the drawings, 2 indicates the transferring cradle, above mentioned, which consists, as clearly shown in Figs. 1 and 2, of a plurality of curved arms secured together by cross pieces, the cradle being pivoted to one of the base rails 4 of the machine frame. This cradle is rocked 60 about its pivotal connection with the frame by a pneumatic mechanism which comprises an air cylinder 6, a piston rod 8 secured to the piston working in said cylinder, and a link 10 pivoted at one end to the piston rod 70 and at its opposite end to the cradle 2. An air valve 12 and suitable pipe connections enable a workman to admit compressed air to either end of the cylinder 6 desired and thus to move the cradle from the position in 75 which it is shown in Figs. 1, 2 and 5 to that in which it appears at Fig. 6, and to lower it again.

The movement of the cradle 2 raises the roll of paper, which previously has been 80 placed on it, into position to roll on to a second cradle 14. This cradle comprises a pair of side bars 16 supporting a series of curved cross pieces 18 on which a covering of boards or other suitable material is fastened. The shape of the cradle obviously 85 will be made to suit the character of the load which it is designed to handle. This cradle is pivoted near one end to the rails 4, one of the pivots being indicated at 20 in Figs. 1 and 2, so that it can swing from a substantially horizontal position in which it receives 90 the roll of paper to a substantial upright position where it discharges the roll, setting it up on one end. The cradle 14 is supported 95 and moved by means of a lever system which is pneumatically operated. This lever system comprises a parallelogram link system consisting of two links 21 and 22 pivoted to the rails 4, or brackets supported 100 by them, at slightly lower points than the pivot 20, and two other links 23 and 24 also pivoted to brackets supported by the rails 4 at points below the pivotal connection of the links 21 and 22. Additional links 25 and 26 connect the links 21 and 23, respectively, to the links 22 and 24, while similar links 27 and 28 connect the upper ends of the links 21 and 22, respectively, with the side bars 16 of the cradle 14. This arrangement allows 105 the entire system to collapse into a very small vertical space when the cradle is in its 110

horizontal position, as shown in Figs. 2 and 3.

In order to raise and lower the cradle adjustable links 29 and 30 connect the ends 5 of the links 25 and 26, respectively, to the ends of arms 31 and 32 both mounted fast on a rock shaft 34 which is supported in the upper part of the frame. Another arm 36 secured fast to the rock shaft 34 is pivoted 10 to the forward end of a piston rod 38 which is secured fast to a piston that slides in a cylinder 40 which is pivoted on the frame at 42, Fig. 2. A valve 44 controls the flow of compressed air through suitable pipe connections to the cylinder 40. When this valve is moved in a proper direction to admit air to the outer end of the cylinder, it forces the piston rod 38 inwardly and acts through the connections just described to 15 raise the cradle 14 from its horizontal position, in which it is shown in Figs. 2 and 3, into a substantially upright position, as indicated in Fig. 1. A reversal of the air supply to the cylinder lowers the cradle again. Fig. 4 shows the cradle in an intermediate position. The free or swinging end of the cylinder 40 is partly counterbalanced by a weight 46 which is connected to the cylinder by a rope 48.

20 It will now be understood that in using the machine the roll R of paper is run on to the cradle 2 while it is in the position in which it is shown in Figs. 1, 2, and 5. The workman then moves the valve 12 in the 25 proper direction to admit air to the rear end of the cylinder 6, which acts through the connections with the cradle 2 to raise the cradle into the position in which it is shown in Fig. 6, where the roll of paper which 30 it previously held is transferred to the cradle 14. The workman next operates the valve 44 to admit air to the forward end of the upper cylinder 40 and thus causes the connections between this cylinder and 35 the cradle 14 to raise the cradle and cause it to upend the roll. The valves 12 and 44 are then reversed to return the cradles 2 and 14 to their original positions. The machine thus accomplishes very quickly an 40 operation which heretofore has been very slow and arduous.

Struts 50 preferably are secured to each of the rails 4 to prevent their buckling under the load. These struts are each provided with a pivoted end 51 which may be swung up into an inoperative position when it is desired to move the machine.

As shown in the drawings, the frame is supported on trucks 52 and, in order to 55 facilitate the movement of the machine in a predetermined direction, a cable or chain 54 is fastened to a small roll mounted on the shank of each truck and a hand lever 56 is connected to this cable to enable the 60 workman to adjust all the trucks simultane-

ously into any desired angular position. The cable 54 is run over idlers or guide rolls 58, as indicated in Fig. 7, to keep it out of the path of movement of the cradle 14.

The invention has been herein illustrated 70 as embodied in a portable machine. It is obvious that under some circumstances the machine might be fixed, in which case it might be desirable to omit the transferring cradle and locate the upending cradle and 75 the operating mechanism therefor in a pit.

It is obvious that the specific design in which the invention is embodied and the details of construction will be varied to 80 suit the requirements of individual cases and that the specific form shown may be modified considerably within the skill of the mechanic and the discretion of the designer without departing from the spirit or scope 85 of the invention.

What is claimed as new is:

1. A machine of the character described comprising, in combination, a cradle mounted for movement from a substantially horizontal position to a substantially upright position, a second cradle arranged to receive the load and movable to discharge the load on to the first cradle, and operating mechanism for said cradles.

2. A machine of the character described comprising, in combination, a cradle constructed and arranged to rock from a load-receiving to a load-discharging position, means for producing said rocking movement of said cradle, a second cradle to which the load is delivered by the first cradle mounted to swing about an axis transverse to the axis of the rocking movement of the first cradle, and mechanism for swinging the second cradle about its axis.

3. A machine of the character described comprising the combination with an upending cradle and operating mechanism therefor, of a transferring cradle mounted beside said up-ending cradle and arranged to rock from a load-receiving position to a position in which it delivers the load to the up-ending cradle, and mechanism for rocking said transferring cradle from either 105 of said positions to the other.

4. A machine of the character described comprising the combination with an upending cradle and operating mechanism for said cradle, of a transferring cradle mounted beside the upending cradle and movable 120 from a load-receiving position to a position in which the load is transferred to said upending cradle, means for operating said second cradle, and a portable frame supporting said cradles and the operating 125 mechanisms therefor.

5. A machine of the character described comprising, in combination, an upending cradle, a link system supporting said cradle, mechanism located above said cradle and 130

- arranged to act through said link system to operate the cradle, a transferring cradle mounted to one side of the upending cradle for movement from a load-receiving position to a load-transferring position, power actuated mechanism for operating said transferring cradle mounted below said upending cradle, and a portable frame supporting said cradles and the operating mechanisms therefor.
6. A machine for handling large rolls of paper comprising, in combination, an upending cradle mounted to swing from substantially a horizontal load-receiving position to a substantially upright load-discharging position, and mechanism for operating said cradle, comprising a lever system including a plurality of links at the opposite sides of the cradle arranged to collapse below the level of the cradle when the cradle is in its load-receiving position, a fluid pressure mechanism, and pivoted connections between said lever system and
- said fluid pressure mechanism enabling said fluid pressure mechanism to move said cradle from one of said positions to the other.
7. A machine for handling large rolls of paper comprising, in combination, an upending cradle mounted to swing from substantially a horizontal load-receiving position to a substantially upright load-discharging position, mechanism for operating said cradle, comprising links moving on stationary pivots and extending substantially parallel to said cradle, said links being arranged to collapse below the level of the cradle when it is in horizontal position, and power operated means acting through said links to move said cradle from one of said positions to the other.

In testimony whereof we have signed our names to this specification.

JOSEPH A. F. NEVINS.
FORREST A. SUTHERLAND.
